United States Patent

Des. 241,973
Patented Oct. 19, 1976

241,973

HAND HELD SPOT LIGHT

Duncan M. Payne, Tulsa, Okla., assignor to
Optronics, Inc.

Filed Sept. 15, 1975, Ser. No. 613,263

Term of patent 14 years

Int. Cl. D26—02

U.S. Cl. D48—24 R

Fig. 1

Fig. 2

Fig. 4

Fig. 3

Fig. 5

FIG. 1 is a front elevational view of a hand held spot light showing my new design.

FIG. 2 is a side elevational view, the opposite side thereof being substantially identical thereto.

FIG. 3 is a top plan view.

FIG. 4 is a rear elevational view.

FIG. 5 is a bottom plan view.

I claim:

The ornamental design for a hand held spot light, substantially as shown and described.
